SPIRAL DRILL COLLAR AND METHOD OF
MANUFACTURE THEREOF

Levi F. Shiplet, Houston, Tex., assignor to Texaco Inc.,
New York, N.Y., a corporation of Delaware
Filed Oct. 21, 1963, Ser. No. 317,593
11 Claims. (Cl. 76—108)

This invention relates generally to the rotary drilling of wells and specifically to an improved drill collar and the method of manufacture thereof.

In rotary drilling, the bit is rotated, with weight being applied to the bit to obtain effective cutting. As the well bore increases in depth, lengths of drill pipe, each normally 30 feet long, are added to form the drill stem, which includes the drill collar, distinct from the drill pipe, adjacent the bit. Through this drill stem, drilling fluids are provided to the bottom of the well bore where the bit cuttings are picked up by the fluids and brought to the surface through the annulus defined by the well bore and/or casing and the drill stem.

Conventional drill collars are made of solid steel billets, usually 30 feet long, to obtain the necessary weight, with the center machined out, e.g. by boring, to the desired inside diameter to define an axial passage. The drill collar is essential to drilling operations because through its weight and rigidity, it helps to keep the drilling of a bore hole straight. Its weight on the bit does not apply compression on the drill pipe and thereby aids in avoiding hole deviation. Frequently, where certain sedimentary formations are abrasive and have low dip angles where fracturing and faulting occur frequently, deviation control becomes difficult.

Accordingly, it is an object of the invention to provide an improved drill collar which will increase the penetration rate of drilling without excessive hole deviation.

It is another object of the invention to provide an improved drill collar which will improve the speed of flow of drilling fluids from the bottom to the top of the well bore and also more easily lift bit cuttings and help to keep the drill bit clean.

Still another object of the invention is to provide an improved drill collar which will act as a stabilizer and hold more weight on a drill bit.

Another object of the invention is to provide an improved drill collar having substantially the same diametral dimension as the drill bit.

Still another object of the invention is to provide a novel method of manufacture of a spiral drill collar.

These and other objects, advantages and features of the present invention will become apparent from the following description of the invention and by reference to the accompanying drawings wherein:

FIG. 1 is a longitudinal view, partly in section, of the embodiment of the drill collar constructed in accordance with the present invention, with an intermediate portion thereof broken away;

FIG. 2 is a cross sectional view on an enlarged scale of a square billet showing the distortion of the original flat faces after twisting and the extent the original corners are cut away; and

FIG. 3 is a cross sectional view, on an enlarged scale, taken along line 3—3 of FIGURE 1, of the spiral drill collar as positioned in a well bore.

In accordance with the illustrated embodiment of my invention, there is shown an improved drill collar which fits into a well bore with close clearance to provide stability and to add more weight on the bit thereby improving deviation control and return flow of fluids and increasing drilling speed.

Referring to FIG. 1, the drill collar constructed accord-

2

ing to my invention is disclosed at 10, having an upper end 11 formed into a cylindrical neck with a threaded box 12 formed therein. The lower end 13 is also formed into a cylindrical neck for the threaded pin 14, which receives the bit sub 15 for holding a suitable rotary type bit 16. There is also disclosed the manner in which a pin 17 at the lower end 18 of another drill collar or a drill pipe is joined to box 12 to form the drill stem. The axial passage through the drill collar is disclosed at 19. The cylindrical necks can be formed by swaging or by machining, e.g. by turning, the square billet at the time that the axial passage is formed, e.g. by boring, and either before or after the billet is twisted.

FIG. 2 discloses the deformation of the original flat faces of the substantially square billet into concave surfaces, resulting when the square billet is twisted counterclockwise about its longitudinal axis of its 30 foot length to provide substantially a right hand screw thread. The amount of twisting is varied according to the type formation being drilled, the velocity of the drilling fluids in the annulus and the rotating speed of the drill string. The corners of the original square billet, indicated as a, b, c and d, should be machined off to give the desired cross-section dimension and to obtain adequate bearing surface 20 against the well bore, the machining to include grinding, turning and/or hogging. The rounding of the corners is indicated at A, B, C, D by dotted lines in FIG. 2 and by solid lines in FIG. 3. The original flat faces, indicated by dotted lines between the corners, now take the concave 25 shape surfaces as indicated in full lines in FIG. 2. The size of the billet is chosen so that its diagonal dimension is slightly larger than the well bore diameter or that of the drill bit so that after it is twisted and the corners machined off, the outside diameter will be slightly less than the diameter of the well bore. This will create a "packed-hole" effect and tend to prevent deviation of the hole.

FIG. 3 discloses in cross section the "filling" or packed position of the spiral drill collar in the bore hole, showing the close contact of the bearing surfaces A, B, C, D at the rounded off corners with the well bore, the flute-like flights formed from the flat face surfaces of the square billet serving as an auger for easy removal of the bit cuttings from the bottom of the well bore along with the drilling fluids. The rotation of the spiral drill collar during drilling provides the lifting effect to the drilling fluids and bit cuttings, and the bearing surfaces act as a stabilizer because of the screw effect on the walls of the well bore, thus reducing the need of separate stabilizers on the drill stem above the bit.

As indicated in FIG. 1, conventional drill collars may be used above the improved spiral drill collar, and where formally a conventional round drill collar would permit weights from 2,000 to 5,000 pounds to be applied on the bit, beyond which weights, considerable hole deviation would occur, the spiral drill collar formed by twisting a square billet can carry 20,000 to 40,000 pounds of weight with 8½ inch drill pipe without excessive hole deviation. Also, two twists per 30 feet of drill collar is considered usual.

Thus, there has been disclosed and described a novel and improved drill collar and method of manufacture thereof, which by putting a twist in a square billet, cuts down on the number of separate stabilizers used, eases the return of drilling fluids and cuttings from the bottom 65 of the bore hole to the surface, and by allowing the application of additional weight on the drill bit, shortens the drilling time because of the increased penetration rate and thus reduces the cost of the drilling.

Other modifications and variations of the invention as hereinbefore set forth may be made without departing from the spirit and scope thereof, and therefore only

such limitations should be imposed as are indicated in the appended claims.

I claim:

1. The method of forming a spiral drill collar for use with a bit having substantially the same outer diametral dimension comprising

- (a) twisting a square hollow member about its longitudinal axis;
- (b) forming the ends of the resulting twisted member into cylindrical necks;
- (c) providing said cylindrical necks at each of the ends of said twisted member with screw threading; and
- (d) rounding the original edges of said square hollow member to provide said drill collar with the desired diametral dimension.

2. The method as defined by step (a) of claim 1, wherein in said twisting comprises two counterclockwise complete turns about said longitudinal axis.

3. The method as defined by step (b) of claim 1, wherein in the forming of the ends into cylindrical necks is accomplished by swaging.

4. The method as defined by step (c) of claim 1, when said screw threading comprises the external threading of a pin at one end of said member and an internal threading of a box at the other end of said member.

5. The method as defined by step (d) of claim 1, wherein said rounding of the edges is accomplished by a machining process.

6. In a method of forming a spiral drill collar of normal length from a substantially square billet, the steps of

- (a) providing cylindrical necks at the ends of said billet;
- (b) forming an axial passage through said billet;
- (c) twisting said billet in counterclockwise direction about its longitudinal axis;
- (d) providing each of said cylindrical necks with screw threading; and
- (e) machining the original edges of said billet to ob-

5

tain a drill collar of the desired dimensions and having spiral grooves.

7. method as defined by step (a) of claim 6, wherein said cylindrical necks are formed by machining.

8. The method as defined by step (a) of claim 6, wherein said cylindrical necks are formed by swaging.

9. The method as defined by step (c) of claim 6, wherein said twisting provides two complete turns.

10. The method as defined by step (d) of claim 6, wherein opposite necks of said collar are provided respectively with internal and external threading.

11. The method of forming a spiral drill collar for use with a bit having substantially the same outer diametral dimension comprising

- (a) forming the ends of a square hollow member into cylindrical necks;
- (b) twisting said square hollow member with cylindrical ends about its longitudinal axis;
- (c) providing said cylindrical necks at each of the ends of said twisted member with screw threading; and
- (d) rounding the original edges of said square hollow member to provide said drill collar with the desired diametral dimension.
